UNITED STATES PATENT OFFICE.

ERNEST EDWARD ROUSE, OF NEWQUAY, ENGLAND.

WATER HEATER.

Application filed May 6, 1920. Serial No. 379,366.

To all whom it may concern:

Be it known that I, ERNEST EDWARD ROUSE, a subject of the King of Great Britain, residing at St. Maur, Newquay, in the county of Cornwall, England; have invented new and useful Improvements in and Relating to Water Heaters, of which the following is a specification.

This invention relates to water heaters and has for its object the provision of an improved construction adapted to employ gas as the heating medium and by which many of the difficulties encountered hitherto in constructing and operating water heaters are avoided.

The apparatus constructed according the invention is self contained and has no external taps, cocks, or piping of any kind, the entire structure being built of elements which are simple and cheap to manufacture. The entire heater is carried by the rotary part of a valve which controls the gas and water supply and which is so constructed that partial rotation of the heater in either direction causes both gas and water supply to be opened or closed simultaneously.

In order to utilize the heat of the gases ascending through the apparatus from the burner to the utmost possible extent these gases are caused to pass through an annular chamber in the centre of which is a column through which incoming water ascends and is preheated. Water is also caused to flow down the outer wall of the annular chamber through a series of annular cups by which it is repeatedly brought into contact with the wall and to ensure that the maximum heating effect is imparted to the wall it is provided with a number of baffles which compel the gases to take a tortuous path and bring them into repeated contact with the wall. The construction of the upper end of the wall is such that the water is continuously heated during its transference from the central column to the exterior of the heated wall whilst to utilize still further the heat of the gases of combustion the latter may be caused to pass through the water during such transference. This latter feature, however, is not essential as the water may be continuously heated during transference without actually coming in contact with the gases.

The invention will now be described with reference to the accompanying drawings in 55 which:

Figure 1 is a sectional elevation of a complete water heater constructed in accordance with the invention.

Figure 2 is a sectional elevation of modified form of head.

Figure 3 is a sectional elevation of another modified form of head.

Figure 4 is a sectional plan of Figure 3 taken on the line A—A. 65

Figure 5 is a plan of the burner ring and

Figure 6 is a sectional elevation of a modified form of burner construction.

The water heating parts of the apparatus are enclosed by a casing 13 of sheet metal 70 or other suitable material secured in any convenient manner to the lower upturned rim 14 of a base 1 carried on the outer edge of a burner ring 41 supported as herein-after described in a casting 38. Disposed 75 vertically in the centre of the casing 13 is a pipe 4 through which incoming water ascends and which extends downwardly below the base 1 and has screwed thereon a conical plug 37 seated in the casting 38 80 which is formed with a gas inlet passage 39 and a water inlet passage 40.

The centre of the plug 37 is hollow and its lower end is closed by a screw threaded stud 42 integral with a nut 43 bearing on 85 a washer 44. The lower end of the pipe 4 opens into the central portion 45 of the hollow passage through the plug 37 which communicates when the valve is open by a port 46 with the water inlet passage 40. The 90 flow of water from the passage 40 to the pipe 4 is controlled by a conical valve head 47 on a spindle 48 carrying an operating wheel 49, the spindle having screw threaded engagement with the stud 42 and nut 43 95 through which it passes so that upon rotation of said spindle the valve head 47 is raised or lowered accordingly.

The upper end of the plug 37 is hollowed out to a larger diameter than the lower portion to provide an annular chamber 50 adapted to communicate, when the valve is open, by a port 51 with the gas inlet passage 39. A boss 52 on the burner ring 100 41 extends downwardly into the annular chamber 50, gas passing through a narrow 105

annular space 53 between the boss 32 and the top 54 of the plug to the burner ring 41 inducing a current of air through an annular passage 55 formed between 5 a peripheral extension 56 of the burner ring 41 curved inwardly beneath said ring and the upper surface 54 of the plug which is curved in conformity with the curvature of the extension 56. Gas and 10 air become mixed in the annular chamber 57 and pass to the burners 41 outlets 58 herein-after described being provided in the base 1 for condensed moisture from the heating chamber which falls into a tray 66 disposed in a dished portion of the upper surface of 15 the casting 38, see Figure 1.

Surrounding the plug 37 on its periphery above the port 51 is an annular groove 59 communicating permanently with gas inlet 20 passage 39 by an inclined passage 60. The groove 59 communicates by a short tube 61 extending across the annular chamber 50 with a by-pass passage 62 formed in the boss 52 and terminates in a short tube 63 curved 25 over above the burners 41. The by-pass 63 is always kept alight and the arrangement of the groove 59 possesses the advantage that any gas which may leak up the surface of the plug 37 when the port 51 is cut off from the passage 39 will enter said groove and be utilized in the by-pass. Similarly any water 30 which may leak up the face of the plug from the water inlet passage 40 enters a groove 64 and leaves the casing by a port 65.

35 A water inlet pipe 67 screw threaded into the casting 38 should preferably be provided with a suitable check device as indicated at 68.

40 The burner ring 41 has formed near its periphery a number of blocks 80, four being shown in the example illustrated, see Figure 5, these blocks being provided on their upper external edges with grooves 81 providing a seating for the base 1 the lower inner edge of which rests in the grooves. 45 Spaces 58 are thereby left between the blocks 80 through which any additional air required for combustion may enter and through which condensed moisture may escape to the tray 66.

45 In the arrangement shown in Figure 6 the construction of the casting 38, plug 37 and parts associated therewith is similar to that shown in Figure 1, the modification consisting in the construction of the burner, by-pass, air inlet and base of the heater. In this arrangement a completely cylindrical casing 13^a is employed and is secured to a base 1^a of smaller diameter relatively to the 50 base 1, Figure 1. The boss 52^a is formed integrally with a tube 69 which forms with the interior of the base 1^a an annular chamber 70, the mouth of which is covered with gauze 82 and constitutes the burner. The tube 69 55 is secured to the base 1^a by screws 71, both

tube and base being provided at the points where the screw holes are situated with protruding machined surfaces 73 to ensure equal spacing of the tube and base at all points. Gas leaves the plug 37 by the annular space 53 as before and enters the annular chamber 70 inducing a current of air beneath the lower edge of the base 1^a, the entry of air being regulated by a ring 74 adjustably secured to the base 1^a as by set screws 75 working in slots 76 in the ring by which the ring may be adjusted vertically.

The by-pass is carried through the plug 37 in the same manner as in Figure 1 but comprises also a tube 77 terminating a short distance above the upper extremity of the tube 69. A number of tubes 78 communicating with a circular groove 79 in the upper surface of the boss 52^a serves to collect condensed moisture and convey it to the tray 66.

The base 1 Figure 1 is preferably provided with vertical ribs or fins 2 forming annular channels 3, the purpose of which will be described hereinafter. A wall 6 forms an upward continuation of the base 1, the upward passage of the gases from the burner being confined to an annular space 5 between the pipe 4 and the wall 6 and the downward passage of the water to an annular space 18 between the wall 6 and the outer casing 13.

The wall 6 is provided with a number of baffles 7 and external annular cups 8 and is built up in the following manner. The baffles and cups are formed by inverted truncated conical members bent inwardly slightly at their upper and larger ends as shown at 9 and provided on the portions destined to form the baffles 7 with serrations 10. The conical members may be formed in any convenient manner.

By providing baffles of this shape it has been found that they absorb heat more readily and radiate it to the annular cups 8 in which water is heated during its descent therefrom.

The wall 6 comprises a number of rings 11 bevelled at top and bottom to provide seatings for the conical members. The complete structure therefore consists of alternating rings 11 and conical members soldered or otherwise secured in correct relative positions, the lowermost conical member resting on and being secured to the upper bevelled edge 12 of the base 1. An outlet 15 for heated water is provided through the rim 14 and casing 13 communicating with a pipe 16.

The wall 6 built up in the manner above described terminates in a head 17 which is 115 formed with a tapered portion 19, through the center of which the upper portion of the pipe 4 extends. A cup 20^a is attached to the upper end of pipe 4, bears on the tapered portion 19 and has a lip 20 of semi-circular 130

cross section, which is flared outwardly and bent over as shown. The tapered portion 19 is provided with ports 21 opposite which is disposed an annular inclined baffle 22.

The casing 13 follows approximately the contour of the head 17 but terminates in an outwardly flared opening 23.

Referring now to Figure 2, which illustrates a device more especially designed for use with high pressure systems, a wall 6 and outer casing 13 are provided as before, the former terminating in a portion 24 of narrower diameter flared outwardly slightly at its upper end. The central pipe or column 4 is open at its upper end and has screw threaded thereon a hollow mushroom head 25 provided on its underside with one or more rings of perforations 26. In the upper side of the head 25 is a boss 27 providing a bearing for a screw threaded spindle 28 carrying at its upper end a milled hand wheel 29 and at its lower end a conical valve member 30 adapted when screwed down to enter the open end of the pipe 4 and limit the flow of water therefrom. The member 30 also acts at all times as a baffle to direct the ascending water towards the perforations 26. The head 25 also carries by means of distance pieces 31 a curved annular baffle 32 the lower end of which terminates at a point closely adjacent to the portion 24 of the wall 6 whilst the upper end of said baffle terminates in a rim 33 adapted to engage and be secured to the upper edge of the casing 13.

The portion 24 of the wall 6 may also if desired be provided with vertical annular ribs or fins 34 forming annular channels 35 around said wall.

A further modification of the head of the apparatus is illustrated in Figures 3 and 4 in which a head 83 terminates the wall 6 and is provided with ports 84 through which the gases from the burner leave the annular chamber 5. The head 83 is screwed on to the upper end of the pipe 4 and is formed with a cup 20^b from which water flows through grooves or channels 85 cut between the ports 84 into the annular space 18. The rate of flow is controlled so that water passes in a thin film over the head and is directed by the shape of the head into the uppermost cup 8 of the series, as shown in Fig. 1.

It is to be noted that in the assembly of the parts above described the central pipe or column 4 forms a connection between the head of the heater and the plug 37. By its screw threaded connection with the upper end of the wall 6 which is made fast before use with the base 1, the latter carrying the casting 13 and the burner ring are secured in position when the plug 37 is secured to the lower end of the pipe 4 allowing the whole apparatus to be rotated in the casting 38.

To effect this rotation for the purpose of turning on or off the water and gas, the op-

erator grasps the outlet pipe 16 or a suitable heat insulated handle which may be attached thereto.

The operation of a water heater constructed according to the invention is as follows:

By means of the by-pass 63 or 77 the burner is ignited simultaneously with the admission of water to the pipe 4 when the apparatus is turned to the position shown in Figure 1 air for combustion being sucked in through the passage 55 (Figure 1) or passage 70 (Figure 6).

The water receives a preliminary heating during its passage to the top of the pipe 4 by the gases of combustion ascending through the annular space 5 and leaving it by the ports 21. The water on leaving the pipe 4 fills the cup 20^b and flows in a thin film over the annular lip 20 in leaving which it encounters the gases issuing from the ports 21 which pass through the falling film of water to which they give up their heat and leave the apparatus by the outlet 23, the heated water being directed by the baffle 22 towards the exterior of the wall 6 where it falls into the first of the series of cups 8. The particular formation of the lip 20 enables heat to be imparted continuously to the water during its transference from the pipe 4 to the annular space 18.

When the construction of head illustrated in Figure 2 is employed the operation is very similar to that of the first form, the water issuing from the top of the pipe 4 filling the head 25 and falling through the perforations 26 in a number of fine streams meeting the hot gases of combustion ascending from the interior of the wall 6. The water descends between the lower end of baffle 32 and the wall 6 and is caught in the annular channel 35 if used and thereby retained for a short time in close contact with the wall 6 to ensure thorough heating. The combustion gases after passing through the water falling from the perforations 26 and imparting heat thereto, pass away through the spaces around the edge of the head 25 between the distance pieces 31 to the atmosphere.

The construction of head illustrated in Figures 3 and 4 is designed for use in cases where it is desired to avoid actual contact between the water and combustion gases. In this case water fills the cup 20^b and flows in a thin film through the channels 85 into the annular space 18, the gases issuing from the ports 84 and leaving by the outlet 23.

The water after passing the head of the apparatus as above described enters the uppermost cup 8 of the series wherein it is subjected to further heating from the adjacent wall 6. As the cup becomes full, the water overflows into the second of the series, this operation being repeated throughout the series of cups 8 and annular channels 3 until,

the heated water leaves by the outlet 15 and pipe 16. By this arrangement very thorough and uniform heating of the water is assured as in each cup the incoming water is cooler than the water already there which latter rises to the surface and falls into the next succeeding cup, this effect being more marked and necessary in the uppermost cups of the series. The rate of feed maintained is such that the water in overflowing from one cup to the next will flow down the under surface of each cup.

The hot gases ascending through the annular space 5 are compelled by the baffles 7 and the serrations 10 therein to assume a tortuous path which brings them into repeated and intimate contact with the inner surfaces of the rings 11 forming the wall 6 whilst the heat imparted to the baffle portions 7 of the cups 8 passes by conduction into the latter whereby the water in said cups is surrounded internally and externally with heated surfaces. The annular channels 3 afford a means of bringing the water into very close contact with the hot gases as they leave the burner, this being the final step in a series of operations by which the water is treated in a number of successive receptacles each hotter than the one preceding it whereby hot water may be obtained in a very short space of time after the burner has been lit.

I claim:—

1. A water heater comprising an outer casing, a central water supply column, a cylindrical wall disposed intermediately of said casing and column, a plurality of downwardly directed baffles carried on the inner surface of said wall, a vertical series of annular cups disposed on the outer surface of said wall and closed at their lower ends, a burner at the lower end of said casing, and means for transferring the water while continually heating same from said column to the first of said series of annular cups.

2. A water heater comprising an outer casing, a central water supply column, a plurality of superimposed cylindrical members forming an annular chamber for combustion products, a plurality of inverted truncated conical members alternating with said cylindrical members to form a series of annular cups externally of said chamber and a series of baffles internally of said chamber, a burner at the base of said casing, and means for transferring the water while continually heating same from said column to said series of cups.

3. A water heater comprising an outer casing, a central water supply column, a cylindrical wall disposed intermediately of said casing and column, a plurality of downwardly directed baffles carried on the inner surface of said wall, a vertical series of annular cups disposed on the outer surface of said wall and closed at their lower ends, a burner at the base of said casing, inlets for gas and water beneath said casing, means whereby partial rotation of said casing serves to open and close the gas and water supplies simultaneously, and means for transferring the water while continuously heating same from said column to said series of cups.

4. A water heater comprising an outer casing, a central water supply column, a cylindrical wall disposed intermediately of said casing and column and secured to said column at its upper end and to said casing at its base, a plurality of downwardly directed baffles carried on the inner surface of said wall, a vertical series of annular cups disposed on the outer surface of said wall and closed at their lower ends, a burner at the base of said casing, means for transferring the water while continually heating same from said column to said series of annular cups, a valve member having gas and water inlets secured to the base of said column, and means whereby partial rotation of the apparatus brings said inlets into and out of communication with gas and water supplies.

5. A water heater comprising an outer casing, a central water supply column, extending below the base of said casing, a plurality of superimposed cylindrical members forming an annular chamber for combustion products, a gas burner at the base of said chamber, a plurality of inverted truncated conical members alternating with said cylindrical members to form a series of annular cups externally of said chamber and a series of baffles internally of said chamber, a connection between the top of said chamber and said column, a connection between the base of said chamber and the casing, means for transferring water from said column across said chamber to said series of annular cups, a valve member having gas and water inlets secured to the base of said column and means whereby partial rotation of the apparatus brings said inlets into and out of communication with gas and water supplies.

In witness whereof I affix my signature.

ERNEST EDWARD ROUSE.
